Patented May 10, 1966

204,712

PLASTIC MERCHANTISING CONTAINER OR THE LIKE

Richard K. Shelby, Downers Grove, Ill., assignor to Monsanto Company, St. Louis, Mo., a corporation of Delaware

Filed Aug. 26, 1964, Ser. No. 81,450

Term of patent 14 years

(Cl. D58—11)

FIG. 1

FIG. 2

FIG. 3

FIG. 4

FIG. 1 is a perspective view of a plastic merchandising container or the like, showing my new design;
FIG. 2 is a side elevational view;
FIG. 3 is a top plan view; and
FIG. 4 is a bottom plan view thereof.

The dominant features of my design reside in the portions shown in full lines.

I claim:

The ornamental design for a plastic merchandising container or the like, as shown and described.
